UNITED STATES PATENT OFFICE.

CLEMENT KELNHOFER, OF MEDFORD, WISCONSIN.

ROAD-SURFACING MACHINE.

Application filed March 21, 1924. Serial No. 700,923.

To all whom it may concern:

Be it known that I, CLEMENT KELNHOFER, a citizen of the United States of America, residing at Medford, in the county of Taylor 5 and State of Wisconsin, have invented certain new and useful Improvements in Road-Surfacing Machines; and I do hereby declare that the following is a full, clear, concise, and exact description of the invention, 10 such as will enable others skilled in the art to which it appertains to make and use the same.

This invention relates to improvements in road surfacing or jointing machines, having 15 for an object to provide a machine of this character which when moved over a dirt or gravel roadway will function to level and smooth the surface thereof, distributing that dirt or gravel loosened into hollows 20 and similar irregularities of such roadway, and rendering it, generally, more efficient for traversing.

It is likewise an object of the invention to provide a road surfacing machine employing novelly mounted and shaped surface scraping and distributing blades, the same 25 being capable of vertical adjustment with a view towards securing proper distribution or placement of the loosened dirt or gravel 30 over the entire roadway surface and also, to permit the desired crowning or similar conditioning of the roadway surface.

Another and equally important object of the invention is to provide the machine with 35 means for scarifying the surface of a roadway to be levelled and graded, the elements thereof being individually or collectively adjustable in order that the desired engagement may be had with the roadway surface 40 for loosening the irregularly arranged or positioned portions of dirt or gravel without disturbing the bed proper of the roadway.

Yet another object of the invention is to 45 provide the machine with an adjustable wheeled mounting, whereby the wheels may be so positioned as to fully engage a surface over which the machine is travelling, or when desired, may be caused to move to inoperative positions with respect to the machine frame, thus permitting the machine 50 to be drawn in sled fashion over the roadway.

Other objects of the invention will be in 55 part obvious, and in part pointed out hereinafter.

In order that the invention and its mode of operation may be readily understood by persons skilled in the art, I have in the accompanying illustrative drawings, and in the detailed following description based 60 thereupon, set out one possible embodiment of the same.

In these drawings:

Figure 1 is a side elevation of the improved machine;

Figure 2 is a top plan view thereof;

Figure 3 is a bottom plan view of the machine;

Figure 4 is an enlarged fragmentary detail, partly in section, taken on the line 4—4 70 of Figure 2;

Figure 5 is a similar detail taken on the line 5—5 of Figure 2;

Figure 6 is an enlarged fragmentary detail, partly in section, taken on the line 6—6 75 of Figure 2;

Figure 7 is a corresponding view taken on the line 7—7 of Figure 2;

Figure 8 is an enlarged fragmentary detail, partly in section, taken on the line 8—8 80 of Figure 2; and,

Figure 9 is a detail in perspective of one of the roadway surface scraping and earth or gravel distributing blades.

Having more particular reference to the 85 drawings, in connection with which like characters of reference will designate corresponding parts throughout, the improved machine may be stated to comprise a substantially rectangular frame comprising a 90 pair of longitudinally disposed relatively parallel I-beams 1, having the opposite end portions thereof transversely connected by bars 2 engaged or connected with adjacent portions of the same as indicated at 3, while bolsters or brace bars 4 are also disposed transversely of the intermediate portion of the frame so constituted by the I-beams 1 and the end bars 2 and are connected to adjacent portions of the I-beams 1, as indicated at 5. A suitable form of draft connection, as generally indicated by the numeral 6, is connected to the forward ends of the I-beams or skids of the machine frame 1, and as will be understood, may be provided with various other forms of coupling devices or the like needed or desirable in connecting or coupling suitable traction means to the machine.

To permit movement of the machine over 110

a roadway or other surface without being drawn in sled fashion, wheels are provided the same, rearward wheels 7 being mounted upon arms 8 pivoted to the inner sides of adjacent rearward portions of the I-beams 1, as indicated at 9; the respective wheels 7 of these arms having suitable bearing upon the intermediate portions thereof, as indicated by the numeral 10, while the outer or free portions of such arms are bent slightly upwardly as indicated at 11 and apertured, whereby connection with a cable or similar means 12 may be effected. In this connection, it will be noted that the arrangement of the rearward wheels 7 upon the pivoted arms 8 is such as to bring the same within or between the rearward portions of the I-beams or skids 1, as clearly shown in the Figures 2 and 3.

In order that means for effecting vertical adjustment of these rearward wheels 7 may be had, whereby their extent of engagement with a surface over which the machine is to be moved may be regulated, a pair of stub shafts 13 are employed, such shafts having their outer ends mounted in suitable bearings formed in adjacent rearward portions of the I-beams or skids 1, as is clearly shown in the Figure 5, while the inner ends thereof have bearing in brackets 14 secured as at 15 to the rearward connecting bar 2 of the machine frame. A circular ratchet 16 is fixedly mounted upon one of the shafts 13, while an operating lever 17 having bifurcated bearing portions formed upon its lower end is loosely mounted upon such shafts 13 adjacent their respective ratchet wheels 16; a pawl 18 being pivotally mounted upon the lower ends of each of the levers 17, and being connected through a rod 19 to a pivoted grip member 20 mounted upon each of the several levers 17, as indicated at 21. In this way, it will be understood that with engagement of the pawl 18 with the teeth of the ratchet wheel 16 fixedly mounted upon the shafts 13, rotary motion may be imparted to the respective shafts 13. As means for limiting pivotal movement of the several levers 17 in certain directions, bracket arms 22 are secured to portions of the rearward cross bar 2 and as will be noted, have shouldered portions 23 formed upon their outer extremities, against which adjacent portions of the levers 17 are adapted to abut. Other pawls 24 are pivoted to the under portion of the rearward cross bar 2 adjacent the opposite ends thereof and in proximity to each of the ratchet wheels 16, as indicated at 25, such pawls being adapted to be normally engaged with the adjacent teeth of their respective ratchet wheels 16 in the manner clearly shown in the Figure 4, while handle-like extensions 26 are formed upon the rearward or lower portions of such pawls and are extended therefrom so that

they may be conveniently engaged and actuated, whereby to disengage the pawls 24 from the teeth of their particular ratchet wheels 16. In this way, it will be understood that irrespective of engagement of the pawls 18 carried upon the levers 17 with the teeth of the ratchet wheel 16, such ratchet wheels will be prevented from having undesirable rotary movement by reason of the normal engagement of the locking pawls 24 therewith. The arrangement of the locking pawls, however, is such as to permit rotary movement to be imparted to the adjacent ratchet wheels 16 through the medium of the levers 17 when said levers are rocked in rearward directions, the movable engagement of the several pawls 18 with their respective ratchet wheels 16 being such as to permit rotary motion to be intermittently transmitted to the several shafts 13 with continued rocking movement of the levers 17. The remaining ends of the cables 12 are connected to the several shafts 13 as is clearly shown in the Figures 4 and 5 and thus, with rotation of the shafts 13 by means of the levers 17, it will be understood that swinging movement will be imparted to the bearing arms 8 and in consequence, vertical movement of the rearward wheels 7 will be effected. Thus, by coiling the cables 12 about the several shafts 13 through the medium of the levers 17, said rearward wheels 7 may have their tread portions brought into engagement with a surface in such a manner as to entirely support the weight or load of the machine frame thereupon. The extent of engagement of such wheels 7 may, of course, be regulated to the desired nicety through the medium of their particular levers 17. When it is desired to have the wheels turned to inoperative positions with respect to the machine frame, it is only necessary to press downwardly upon the extended handle portions 26 of the pawls 24, thus disengaging said pawls 24 from the teeth of their respective ratchet wheels 16, whereupon the stress imparted to the shafts 13 will be sufficient to cause rotation of such shafts in a reverse direction, permitting outward swinging movement of the bearing arm 8 with the resultant return of the rearward wheels 7 to their inoperative positions.

The forward end of the machine frame is supported upon a single wheel indicated herein by the numeral 27, said wheel being provided with curved bearing forks 28 carrying a vertical pivot pin or pintle 29 upon the upper extremities thereof, which pivot pin is received in a suitable form of bearing bracket 30 secured to a slidable arm or plate 31 received in suitable guides formed in vertically disposed brackets 32, which brackets, as will be noted, are fixedly secured by bolts or other suitable fastening devices to the forward cross bar 2 of the

machine frame, as indicated by the numeral 33. A lip 34 having a screw threaded opening formed in its intermediate portion is provided upon the upper end of the bracket 32 and receives therethrough a vertically disposed screw threaded shaft 35, the upper end of which is squared in cross section and indicated by the numeral 36, while the lower end thereof has swivel connection with a bearing arm 37 secured to the intermediate portion of the vertically slidable plate 31. Thus, by rotating the screw threaded shaft 35 in a suitable manner, such as by engaging a handle, wrench, or other device with the squared end 36, the wheel 27 may be either raised or lowered and in this way, the forward end of the machine frame may be partially or wholly supported upon the wheel, or if desired, the wheel may be moved to an inoperative position, whereupon the I-beams or skids 1 of the machine will fully rest upon the surface and thus permit the machine to be drawn thereover in sled fashion.

25 Bracing rods 38 may be and preferably are secured to the upper portions of the bracket 32 and extended diagonally into engagement with portions of the forward ends of the I-beams 1, as indicated by the numeral 39.

With a view towards providing the machine with means for scarifying a surface over which the same is drawn either upon its wheels or in sled fashion, I provide a scarifier, indicated in its entirety by the numeral 40, such scarifier comprising a beam or supporting bar disposed transversely of the machine frame as is clearly shown in the Figures 2 and 3 and having its opposite ends connected to and supported upon bracket arms 41 pivoted to the inner side and forward portions of the several I-beams 1, as indicated by the numeral 42. A plurality of tooth-like elements or spikes 43 are arranged upon the forward portion of the beam of the scarifier, which as shown in the Figure 6, is arranged at angles to the perpendicular axis of the machine, in equidistant relation, and are secured in such positions upon the scarifier beam through the medium of a plurality of U-shaped bolts 44 adapted to snugly engage or hug the adjacent portions or shanks of the tooth elements 43. Thus, when these bolts 44 are tightened, said tooth elements 43 will be positively retained in their angular position with respect to the frame of the machine and furthermore, their positioning upon the scarifier beam may be varied so that they can engage the surface of a roadway to be levelled or graded to the desired depth.

To permit of collective vertical adjustment of the scarifier presented by the arrangement of the tooth elements 43 upon

the beam hereinbefore described, bracket arms 46 are mounted upon adjacent portions of the I-beams 1 in proximity to the opposite ends of the scarifier beam and receive through screw threaded openings formed therein vertically screw threaded shafts 47, the upper ends of which are squared or similarly formed as at 48, while the lower ends thereof have swivel connection as at 49 with the adjacent portions of the oppositely disposed arms 41. Thus, by turning the screw threaded shafts 47 in the proper direction, it will be understood that upward or downward movement of the scarifier 40 may be effected, whereby the tooth elements 43 thereof may be collectively brought into engagement with a surface to be treated to the desired depth.

Individual adjustment of the various tooth elements 43 of the scarifier 40 may, of course, be effected, by loosening the clamping bar 44 and then individually moving the tooth elements 43 to the desired adjusted positions, whereupon the clamping bar 44 is reengaged with the same for holding them in their fixed positions.

As means for scraping and distributing the dirt or gravel loosened by the scarifier 40 during movement of the surfacing machine or jointer over the roadway, there is arranged between the several I-beams or skids 1, a beam 50, one end of which has slidable connection through a suitable form of bracket 51, with the inner side of one of the I-beams 1; the remaining end of the beam being connected, as at 52, to the adjacent end of a supporting and bracing bar 53, said bar having its remaining end hingedly or pivotally connected as at 54 to the inner portion of the aforesaid I-beam 1. In this connection, it will be noted that the positioning or the arrangement of the beam or bar 50 is at angles to the transverse axis of the machine frame.

An elongated transversely curved scraping blade 55 is secured by suitable devices to the forward portion of the beam 50 and has the scraping edge thereof projected below the lower marginal portion of said beam 50. Thus, it will be understood that the dirt or gravel loosened by the scarifier 40 will be taken up by the blade 55 and with movement of the machine over a roadway, will serve to distribute such loosened dirt or gravel transversely over the roadway, thus filling in any hollows, ruts or similar irregularities with the same.

As stated hereinbefore, one end of the beam 50 has slidable connection through one of the I-beams 1 through the bracket 51, and in order that vertical adjustment of the beam 50 together with the scraper blade 55 may be effected at this connection, there is fixedly mounted upon the upper end of said I-beam a bracket arm 56, having a screw

threaded opening formed therein through which a vertically disposed screw threaded shaft 57 is received, the upper end of the shaft being formed with a squared extension 58 whereby to permit the engagement of a wrench or similar tooth therewith, while the lower end of the shaft has swivel connection as at 59 with a portion of the web of the beam 50.

10 Further vertical adjustment of the beam 50 is permitted by the engagement of a vertically disposed screw threaded rod 60 in a suitably screw threaded opening formed therefor in one portion of one of the bracing bars 4, as shown in the Figure 2, the lower end of such rod 60 having swivel connection with the adjacent end of the beam 50, as indicated at 61 in the Figure 3. Thus, with rotation of the rod 60 in the proper direction, the end of the beam 50 connected thereto may be raised or lowered.

With a view towards providing another form of surface scraper and dirt or gravel distributor, there is arranged upon the machine frame, a second beam 50', carrying a scraper blade 55', this beam 50' and the scraper blade 55', however, being arranged at an angle opposite to that in which the beam 50 and its scraper blade 55 are arranged, as is clearly shown in the Figures 2 and 3. Thus, it will be understood that loose dirt or gravel passing from the rearward end of the scraper blade 55 will be taken up by the blade 55' and thus moved in an opposite direction transversely across a roadway being treated, graded, or jointed with the improved machine.

Inasmuch as the construction and mounting of this beam 50' and its scraper blade 55' is identical with that described in connection with the beam 50 and its scraper blade 55, no further reference or description of the same is necessary in this particular connection, it sufficing to state that vertical adjustment of the beam 50' and its scraper blade 55' is effected through the medium of vertically disposed screw threaded shafts 57' and 60'.

After the loosened dirt or gravel has been distributed transversely of the roadway being treated in opposite directions through the medium of the scraper blades 55 and 55', it is desirable to provide further means for effecting positive distribution of such loosened matter, together with proper grading of the same, and to accomplish this, I provide the machine with a transversely disposed bar or beam 62, engaging the opposite ends thereof in vertically disposed guide ways formed by the arrangement of angle bracket plates 63 upon the inner side and rearward portions of the I-beams 1, as clearly shown in the Figure 4. A scraper blade 64 is connected to the forward portion of this beam 62 and has the lower portion

thereof curved outwardly and extending for a distance below said beam 62 whereby to effect engagement of the same with the surface of a roadway being treated with the machine.

Angular bracket arms 65 are fixedly connected to portions of the I-beams 1 in proximity to the opposite ends of the vertically slideable beams 62 and have screw threaded openings formed in the upper portions thereof through which vertically disposed screw threaded shafts 66 are passed; the upper ends of these shafts being squared, as indicated at 67, while the lower ends thereof have swivel connection with adjacent portions of the upper side of the beam 62, as indicated at 68. Thus, it will be understood that the beam 62 with its scraper blade 64 may be either elevated or lowered with respect to the machine frame so as to vary the extent of engagement of the scraper blade 64 with the surface of a roadway.

To prevent the chattering or undue vibratory movement of the beam 62 together with its scraper blade 64 during usage of the machine, I may and preferably do provide longitudinally disposed spaced brace rods 69, bifurcating the opposite extremities thereof and connecting the same to opposite portions of the beam 62, as indicated at 70, while the rearward extremities of such rods are connected to adjacent portions of the rearward beam 2 of the machine frame construction. In this connection, it is to be understood that sufficient flexing of the brace rods 69 at their points of jointure with the beams 62 to allow of vertical adjustment of the beams 62 will be permitted.

I have also found it advisable to provide flexible brace rods 71 for the scarifier 40, connecting the rearward ends of these brace rods 71 to a portion of the scarifier beam as at 72, while the forward ends of such rods are passed through the web portion of the forward cross bar or beam 2 and then secured by locking nuts or similar means as indicated at 73.

I have also found it practical and advisable to brace the intermediate portion of the machine frame with truss rods 74, arranging such rods in diagonally opposed relationship as clearly shown in the Figure 2 and connecting the opposite ends thereof to adjacent portions of the I-beams 1, in the manner indicated by the numeral 75.

The operation of my improved road surfacing or jointing machine may be reviewed as follows:

The wheels 7 and 27 of the machine frame, if to be used, are adjusted by their respective levers 17 and the screw threaded rod 35, so that they will engage with the surface of a roadway to the desired extent. If, however, the wheels are not to be used for supporting the machine, they may be caused to move to their inoperative position, where-

upon the lower portions of the I-beams 1 thereupon. Likewise, the machine may be advantageously employed in the rebuilding of dirt or gravel roads, where it is vital to provide an effectual form of grading means for the roadway. 70

5 The machine is hooked to a tractor or other suitable form of traction means and with the scarifier 40 and the scraper blades 55, 55' and 64 properly adjusted to engage the roadway surface to the desired depth, 10 the machine will function to stir up the immediate surface of the roadway and that dirt or gravel loosened will, with continued movement of the machine, be brought into engagement first with the scraper blade 55 15 moving diagonally and transversely along the beam 50 and transversely of the roadway, during which time it will fill in any ruts, hollows or irregularities of the roadway surface. The residue of the loosened 20 dirt or gravel will now pass from the blade 55 and be taken up by the blade 55' and returned in its transverse diagonal course across the roadway surface being treated. Any dirt or gravel remaining upon the blade 25 55' will be passed from the free end thereof and the transversely disposed scraping blade 64 will engage the same and move it to one side or the other of the roadway if not depositing the same in any irregularities occurring on the roadway surface. 30

As stated hereinbefore, the vertical positioning of the scraper blades 55, 55' and 64 may be brought to the desired nicety through their moveable mounting upon the 35 machine frame and to facilitate rotation of the screw threaded rods connected thereto whereby to effect such vertical adjustment, I may provide a hand wheel 76, the hub portion of said wheel being provided with 40 a squared opening of a size and shape such as to permit the same to be universally fitted upon the squared extensions formed upon the upper ends of each of said vertically disposed screw threaded shafts. Of course, it 45 will be understood that any form of tool may be substituted in lieu of this wheel, such as conditions or preference may dictate.

In actual usage of my improved road surfacing or jointing machine, I have found 50 the same to be highly efficient in the dressing of all rut or pitted gravel roads, or for removing any unevenness or other irregularities occurring upon dirt or gravel roads, thus permitting the maintenance of such 55 roads to be kept at their peak of efficiency with but little effort upon part of a user of the machine.

The machine has also been found to be 60 practical for use in connection with the preparing of highways, where it is intended to apply tarvia, calcium chloride, or other preparations to the roadway, the machine herein serving as an effectual means for smoothing or grading the sub-grade or bed of the 65 roadway before the composition is placed

thereupon. Likewise, the machine may be advantageously employed in the rebuilding of dirt or gravel roads, where it is vital to provide an effectual form of grading means for the roadway. 70

Manifestly, the construction shown is capable of considerable modification, and such modification as is within the scope of my claims, I consider within the spirit of my invention. 75

I claim:

1. A road surfacing machine comprising a frame including skid-like side members, transversely disposed brace bars arranged upon the frame, scraping blades extending 80 diagonally and transversely of said frame, beams extending diagonally and transversely of the frame having certain of their ends hingedly connected to portions of the opposite side members of said frame and their remaining ends connected to the adjacent ends of the corresponding blades, means for effecting vertical adjustment of said blades throughout their lengths, and surface scarifying means mounted upon said frame forwardly of the blades. 90

2. A road surfacing machine comprising a frame including skid-like side members, a plurality of diagonally extending blades arranged between the side members of said frame, certain of the ends of said blades having slidable connection with the side members adjacent thereto, oppositely disposed diagonal beams hingedly connected at certain of their ends to certain of said side members and fixedly connected at their remaining ends to the adjacent ends of their respective blades, means for effecting vertical adjustment of said blades with relation to the frame, vertically adjustable scarifying means mounted upon the frame forwardly of said blades, and wheels mounted for vertical adjustment upon portions of the frame. 100

3. A road surfacing machine comprising a frame including skid-like side members, a plurality of diagonally arranged blades positioned between the side members of said frame, certain of the ends of said blades having vertically slidable connection with certain of the side members, oppositely disposed diagonally extending beams hingedly connected to portions of certain of the side members and having their remaining ends fixedly connected to the remaining ends of said blades, manually operable means for effecting vertical adjustment of said blades with respect to the frame, a scarifier disposed transversely of the frame forwardly of said blades having slidable connection with portions of said side members, manually operable means for effecting vertical adjustment of said scarifier, and wheels mounted for vertical adjustment upon portions of said frame. 110

115

120

125

130

4. A road surfacing machine comprising a frame including skid-like side members, oppositely arranged diagonally extending scraping blades positioned between the side members of said frame intermediate the ends thereof, certain of the ends of said scraping blades having slidable connection with certain of said side members, beams hingedly connected at certain of their ends and in opposed relation to portions of said side members and having their remaining ends fixedly connected to the adjacent ends of their respective scraping blades, manually operable means for effecting vertical adjustment of said blades with respect to the frame, a scarifier including a transversely disposed beam having slidable connection with portions of said side members, tooth elements arranged in spaced relation upon said beam, means for clamping said tooth elements in adjusted position upon the scarifier beam, manually operable means for effecting vertical adjustment of the scarifier beam with respect to the frame, and a plurality of wheels mounted for vertical adjustment upon portions of said frame.
5. A road surfacing machine comprising a frame including skid-like side members, a pair of opposed diagonally extending scraping blades positioned between the side members of said frame and intermediately of the opposite ends thereof, certain of the ends of said scraping blades being arranged in spaced relation from certain of the side members of the frame, said scraping blades having slidable connection with the adjacent side members, beams hingedly connected to certain of the side members and disposed in opposed diagonal relationship, the remaining ends of said beams having connection with the remaining ends of their respective scraping blades, manually operable means for effecting vertical adjustment of said scraping blades, another scraping blade disposed transversely of the frame and rearwardly of the first mentioned blades, said last mentioned blade having vertically slidable connection with said side members, a scarifier disposed transversely of the frame and arranged forwardly of said first mentioned blade, said scarifier including individually adjustable tooth elements, manually operable means for effecting vertical adjustment of said scarifier with relation to the frame, and a plurality of wheels mounted for vertical adjustment upon portions of the frame.

In witness whereof I have hereunto set my hand.

CLEMENT KELNHOFER.
